UNITED STATES PATENT OFFICE.

ANGUS E. DETWILER, OF OXFORD, MICHIGAN, ASSIGNOR OF ONE-HALF TO WILLIAM REED, OF OXFORD, MICHIGAN.

ROAD-SCRAPER ATTACHMENT FOR TRACTORS.

Application filed March 16, 1922. Serial No. 544,288.

To all whom it may concern:

Be it known that I, ANGUS E. DETWILER, a citizen of the United States, residing at Oxford, county of Oakland, State of Michigan, 5 have invented a certain new and useful Improvement in Road-Scraper Attachments for Tractors, and declare the following to be a full, clear, and exact description of the same, such as will enable others skilled in the art to which it pertains to make and use the same, reference being had to the accompanying drawings, which form a part of this specification.

My invention relates to a road scraper attachment for tractors shown in the accompanying drawings and more particularly pointed out in the following specification and claims.

This invention is designed as an attachment for the so-called Cletrac or Cleveland tractor. It may however be applied to any tractor for which it is adapted.

The primary object of the invention is to provide an inexpensive road scraper attachment simple and rigid in construction and operation that may be readily attached or removed from a tractor as required and not apt to get out of order.

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a side elevation of a road scraper attachment installed upon a Cletrac type of tractor, shown in dotted lines.

Figure 2 is a plan view of the same.

Figure 3 is a cross-sectional view taken on or about line 3-3 of Figure 2 showing the re-inforcing angle irons secured to the wall of the scraper.

Figure 4 is a detail sectional view through the nut for securing the side supporting arms of the scraper to the rear axle of the tractor.

Referring now to the letters of reference placed upon the drawings:

55 A, denotes a tractor; B, B, its track

wheels; C, a continuous thread carried by the track wheels. D, is a scraper arc-shaped in cross-section formed of sheet metal reinforced by suitable angle irons E riveted to the back of the scraper. F, F, are side 60 rails terminating in a shoe F' at their forward ends to which the scraper is secured. Bolted to the rear end of the rails F, F, is a fitting G adapted to rock upon the socket nut H, the socket being tapped to engage 65 the threaded end of the rear axle. I, I, are rock-arms pivoted at I' to the side rails F. J, denotes a roller journaled in the rock-arms I, and K is a link bar pivoted to one 70 of the rocker arms and to a manually operated lever L, pivoted at L' to the side rail F. M, denotes a segmental ratchet bolted to the rail F and N is a dog pivoted to the lever L adapted to engage the ratchet. N' 75 is a link bar connecting the dog with an operating lever N², in turn pivoted adjacent to the handle L² at the upper end of the lever L,—for releasing the dog when required. P, P, are radius rods pivoted at one end to an I-bolt P', attached to the side rails F and 80 to the end of the tractor frame. P² P² are turn buckles for adjusting the tension of the rods.

Having indicated the several parts by reference letters the construction and operation 85 of the device will be readily understood.

The scraper D is preferably secured to the side rails F at an angle to the direct thrust of the tractor. The scraper may be adjusted to a higher or lower altitude to suit the 90 requirements of the work by manually adjusting the lever L, whereby the rock-arms I may be tilted to cause the roll J to either contact with the road surface whereby the scraper D may be raised above the surface 95 of the road to any desired degree within the limit of the throw of the lever. The scraper when adjusted may be held in the adjusted position by the dog N engaging the segmental ratchet M.

The convex end J' of the roller reduces the resistance when turning and for this reason the end of the roller is given an arc-shaped form,—as indicated in the drawings. This form however is not essential to the operation 105 of the device.

Having thus described my invention what I claim is:

1. In combination with a tractor, a pair of arms respectively pivoted to each side of 110

the tractor and projecting beyond its forward end, a scraper secured to the forward end of the arms, a pair of rocking levers pivoted to the arms, a roller journaled in the 5 rocking levers, and means for tilting the rocking levers, whereby the roller may be raised or lowered to adjust the altitude of the scraper.

2. In combination with a tractor, a pair of 10 arms respectively pivoted to the axle on each side of the tractor and extending beyond the forward end of the latter to support a scraper, a scraper secured to the forward end of said arms, a pair of rocking levers pivoted to the arms, a roller journaled in said rocking levers, a manually operated lever, a link bar connecting one of the rocking levers with the manually operated lever and means for securing the manually operated lever when adjusted.

3. In combination with a tractor, a pair of 15 arms respectively pivoted to each side of the tractor and projecting beyond its forward end, a scraper secured to the forward end of the arms, a pair of radius rods pivoted to the forward end of the arms and to the frame of the tractor, means for increasing the tension of said rods, a pair of rocking levers pivoted to the arms, a roller journaled in the rocking levers and means for 20 tilting the rocking levers, whereby the roller may raise or lower the altitude of the scraper.

4. In combination with a tractor, a pair 25 of arms having an arc-shaped foot piece at one end, an arc-shaped scraper bolted to the foot piece of the respective arms, a bored fitting secured to the opposite end of each of

the arms, a socket nut extending through the bore in each fitting having a screw threaded 40 engagement with each end of the axle, rocker arms pivoted to said arms, a roller journaled in the rocker arms and means for tilting the rocker arms, whereby the roller may be raised or lowered to adjust the altitude of 45 the scraper.

5. In combination with a tractor, a pair 45 of arms respectively pivoted at one end to the axle of the tractor having a lateral extension at their forward ends, a scraper secured to said lateral extension, means secured to the scraper for re-inforcing the latter, rocking levers pivoted to said arms and a roller journaled in the rocking levers adapted to bear upon the road surface to raise or 55 lower the scraper.

6. In combination with a tractor, a pair 50 of arms pivoted to the axle on each side of the tractor and extending beyond the forward end of the latter to support a scraper, 60 a scraper secured to the forward end of the arms, a pair of rocking levers pivoted to the arms, a roller journaled in said rocking members having convex ends, whereby it may more readily follow the direction taken 65 by the tractor and a manually operated lever connected with the rocking levers for tilting said roller whereby the altitude of the scraper may be raised or lowered.

In testimony whereof, I sign this specification in the presence of two witnesses.

ANGUS E. DETWILER.
